INVENTOR:

ELMER E. FREY.

By Anton Glazewski ATTY.

UNITED STATES PATENT OFFICE.

ELMER E. FREY, OF LONG BEACH, CALIFORNIA.

TIME SWITCH.

Application filed May 17, 1920. Serial No. 382,679.

To all whom it may concern:

Be it known that I, ELMER E. FREY, a citizen of the United States, and resident of Long Beach, county of Los Angeles, State of California, have invented a new and useful Improvement in Time Switches, of which the following is a specification.

My invention relates to a switch operating means, and has especial reference to a mechanism for automatically controlling the switching on and off, respectively, of an electric light or lights, in predetermined sequence, an object of the invention being to provide a simple, cheap and convenient arrangement in which the movement of the switch may be effected at any predetermined time or times, to the end that the automatic lighting of store windows and the like, may be accomplished at a definite time and the extinguishment of the lights accomplished at a predetermined later time, thereby to dispense with the necessity for manual attention.

Other objects will appear from the subjoined specification in connection with the accompanying drawings which represent a preferred form of embodiment of the invention, and in which:—

Figure 1 is a broken rear view of the operating mechanism, in combination with an electric switch and arranged to operate in combination with a time clock.

Figure 2 is a front view of a clock showing the index fingers and trigger, and

Figure 3 is a side and rear view of the trigger bar.

In the construction of my invention I prefer to associate same in combination with an alarm clock of usual construction, adapting the train of gears of the alarm mechanism to transmit the motive power for mechanically operating the switch; and the shaft of the hour hand, on the face of the clock, to carry, with a frictional fit, the index discs and fingers to trip the trigger mechanism at the desired pre-determined hours.

A preferred form is the frictional mounting of the respective discs 1 and 2 on the shaft 3 of the hour hand 4, each of the respective discs having arranged on its face, the numerals one to twelve, corresponding to similar numerals on the dial 9. Each disc 1 and 2 is provided with a finger 5 and 6 respectively, arranged to operate a trigger stud 7, extending through an aperture 8 in the dial 9 and in the path of travel of the

fingers 5 and 6 during their movement around the dial conjointly with the movement of the hour hand 4.

Slidably fulcrumed on a plate 10 in the rear of dial 9 and held in operative position by means of headed studs 12 is a trigger bar 14 carrying integral with and toward its upper end, the trigger stud 7, and towards its lower end being bent upon itself in practically a U form 15, as shown in Fig. 3, the end of the upwardly extending portion 16 being shaped in form of an irregular T. The short arm 17 of the T, while in normal position, forms a stop and holds a finger 18, which is integral with a pinion shaft 19, against revolution. The complementary and longer arm 20 of the T extends in the pathway of travel of spaced studs 21, 21', 21'', and 21''', provided on a webbed gear 22. To the shaft 23 of said gear 22 is secured the inner end of a ribbon spring 24, the opposite or complementary end being secured to the stud 25 of the main frame; and a key 26 for winding said spring being secured in position on the shaft 23.

The end 30 of a spring 28 rests normally in a lip 32 formed in the side of the trigger bar 14, and exerts tension on the trigger bar to hold the same in normal inoperative position.

Slidably secured to the vertical frame 33 by means of headed studs 34, is an operating bar 36, the upper end 37 of which is positioned in the path of travel of a stud 38 provided on the webbed gear 22. The lower end 39 of said bar is provided with a horizontal slot 40, for purposes appearing hereinafter.

Paralleling and acting in conjunction with the operating bar 36, is a link bar 41, the upper end 42 of which is pivotally attached to the end of one arm 43 of a bell crank lever 44, which is fulcrumed on a stud 45 in frame plate 33. The other arm 46 of the bell crank lever 44 is disposed in the path of travel of the stud 38 on the webbed gear 22. On the lower end of the link bar 41 is a stud 47 which passes through and engages in slot 40 of the bar 36, and which is electrically insulated from a blade 48 of a switch 49, the circuit wires leading to and from said switch being indicated by Figures 50 and 50'.

In setting the mechanism to operate the "cutting-in" of the electric switch at the hour desired, the disc 1, positioned on the

dial face 9, is manually moved around on its frictional center until the time numeral thereof corresponding to the time desired, is positioned immediately under the hour hand 4 of the clock (as seen in the accompanying drawings where the time numeral "9" is so positioned); regardless of the position of the hour hand. In like manner, when setting the mechanism to "cut-out" the switch, the disc 2 is manually turned in a similar manner, to bring the time indicating numeral thereon corresponding to the hour desired, in a like position under the hour hand 4, as illustrated in the accompanying drawing, wherein the numeral "10" on the disc 2 is shown so positioned. When the respective discs 1 and 2 are set, as explained, the operation of respectively closing and opening the switch 49 will occur at the appointed time, regularly, each twenty-four hours, so long as the clock mechanism is kept wound.

Observing the sequence of action during the operation of the aforementioned mechanism, it will be seen that, as the hour hand 4 reaches the appointed time for "cutting-in" the electric switch, the finger 5 of disc 1, which has been manually set on the hour hand, and travels around the dial conjointly with said hand, contacts with, and presses the trigger stud 7, together with the upper portion of the trigger bar 14, from normal position. By this action the bar 14, which is slidably fulcrumed on stud 12, is moved about its fulcrum and the stop 16 carried out of operative position with finger 18 of pinion shaft 19. The pinion shaft, being thus released, immediately commences to rotate under the tension and power of the ribbon spring 24, which power is transmitted to the pinion through the train of gears as presently described.

Mounted upon pinion shaft 19 is a pinion 51 in mesh with and operated by spur gear 52, which carries on its shaft a pinion 53 in mesh with and operated by spur gear 54, said spur gear having on its shaft a pinion 55 in mesh with the webbed or driving gear 22, on whose shaft is operatively mounted the inner end of the actuating spring 24, and the outer end of which spring is anchored to a stud 25 of the main frame.

The movement of the bar 14 to release the stop 17 from contact with the finger 18, brings the arm 20 in the path of travel of the respective studs 21, 21', 21'' and 21''' of said webbed gear 22, whereupon each respective stud at definite intervals of time and in succession engages the under edge of arm 20 and raises same together with the trigger bar 14. This action carries the trigger stud 7 above the point of finger 5 of disk 1; when the respective stud, for instance 21, during its rotations with the gear 22, escapes contact with the arm 20, the bar

14, under the downwardly directed tension of the spring 28, returns to its normal position, bringing the trigger stud 7 onto the opposite side of finger 5 of the disk 1 and in position for engagement with the disc 70 finger 6, at its appointed hour. The return to normal position of bar 14 and consequent engagement of the stop 17 with the finger 18 of the pinion shaft 19, immediately arrests the revolutionary movement of the 75 train of gears and holds the webbed gear 22 at rest. Each consecutive series of operations causes the webbed gear 22 to revolve one quarter of a revolution. It is obvious that the above cycle of movements will occur at each contact of the respective disc fingers 5 and 6 with the trigger stud 7, during each respective revolution thereof around the dial, and hence the operation repeated 80 each consecutive twelve hours.

Having described in detail the movement of the timing and tripping mechanism, the actuation and movements of the switch may readily be understood from the following description:—

At the predetermined hour set for "cutting-in" the switch 49, and immediately upon the commencement of the previously described movement of the train of gears, the stud 38, on the webbed gear 22, engages the top 37 of the slideable bar 36, which, in its normal position, lies within the path of travel of the stud 38, presses the slideable bar 36 downwardly; and effects the closing of the switch blade 48, whereby the electrical circuit is closed. Simultaneously with this movement the link bar 41, is drawn downwardly causing the complementary arm 46 of the bell crank lever 44 to be moved in the pathway of travel of the stud 38.

When the mechanism is set in motion at the predetermined hour set for "cutting-out" the circuit, the stud 38 contacts and moves with the complementary arm 46 of the bell crank lever 44 out of its pathway, 110 such action causing the crank lever to fulcrum on the stud 45 and thus to raise the link bar 41, pivotally connected with the arm 43, and the switch blade 48. This movement also returns the top 37 of the bar 36 to its normal position in line with the travel of the stud 38, preparatory for the succeeding operation of "cutting-in," but it will be observed that the stud 38 is so spaced with respect to the studs 21, 21', 21'' and 21''' 120 that there will occur two succeeding operations of the timing and tripping mechanism before the stud 38 will again arrive at the point of operation of the bar 36.

What I claim is:—

1. An automatic switch consisting, in combination with an alarm clock, the gear train for operating same and the hour hand carrying shaft, of two fingered disks frictionally mounted on said shaft, a fulcrumed bar

- provided with a pin disposed in the path of said fingered disks, said bar formed with means to lock the gear train against revolution and with means actuatable by members on one of the gears of the train to operate said bar when the train is released by engagement of the fingered disks with the bar, and cause the pin on said bar to be lifted above and behind the fingers of said disks, 10 a stud on one of the gears of the train, a switch operating lever having its upper end disposed in the path of said stud and arranged to close the switch when the gears are released, and a resetting and switch opening lever pivotally connected to said switch lever and having one end thereof in line with the travel of said stud.
2. An automatic switch consisting, in combination with an alarm clock, the gear train thereof for operating the same, and the hour hand carrying shaft, of two fingered disks frictionally mounted on said shaft, a fulcrumed, slidable trigger-bar provided with a pin disposed in the path of said fingered disks and formed with means for locking said gear train against revolution and with an arm, one of the gears of the train provided with a plurality of members arranged to operate said trigger-bar when released by one of said disk's fingers and cause the pin to be lifted to behind the finger of one of said disks, a spring to hold said trigger-bar under tension to cause same to return to normal position when the members of the gear escape from the arm, a stud 25 on said gear, a switch operating bar having one end in the path of movement of said stud, and a lever co-operating with said switch operating bar and operable by said stud to re-set the switch bar and open the 30 switch.
- 20 In testimony whereof I affix my signature.
